US0D1044487S

(12) **United States Design Patent** (10) **Patent No.:** **US D1,044,487 S**
Jeker (45) **Date of Patent:** **** Oct. 1, 2024**

(54) **CONNECTING DEVICE FOR PARTS OF FURNITURE AND/OR PARTS OF MACHINES**

(71) Applicant: **Lamello AG**, Bubendorf (CH)

(72) Inventor: **Patrick Jeker**, Brislach (CH)

(73) Assignee: **Lamello AG**, Bubendorf (CH)

(**) Term: **15 Years**

(21) Appl. No.: **35/519,008**

(22) Filed: **Nov. 14, 2022**

(80) **Hague Agreement Data**

Int. Filing Date: **Nov. 14, 2022**

Int. Reg. No.: **DM/225440**

Int. Reg. Date: **Nov. 14, 2022**

Int. Reg. Pub. Date: **Nov. 17, 2023**
